UNITED STATES PATENT OFFICE.

EDWARD POHL, OF PATERSON, NEW JERSEY.

SILK-THREAD-FINISHING MACHINE.

No. 909,332.

Specification of Letters Patent.

Patented Jan. 12, 1909.

Application filed August 27, 1907. Serial No. 390,295.

To all whom it may concern:

Be it known that I, EDWARD POHL, a subject of the Crown of Austria, and a resident of Paterson, county of Passaic, State of New Jersey, have invented certain new and useful Improvements in Silk-Thread-Finishing Machines, of which the following is a specification, reference being had to the accompanying drawings, forming a part thereof.

10 My invention relates to improvements in silk thread finishing machines, and particularly to means in which said threads are treated individually, as distinguished from appliances in which the threads are treated 15 in bulk such as in skeins. In apparatus of this character the threads are first passed through a finishing solution, and are then carried over a heated contact surface, with the result that they are dried, ironed and lustered. Finally they are wound up upon 20 spools by means of suitable winding mechanism. The heated contact surface in this class of machine is usually a flat horizontal steam heated table, being of sufficient width 25 to support and engage all of the threads treated in any particular machine.

In the present form of machine I provide an individual contact member for each thread, such contact member being in the 30 form of a vertically disposed tube preferably polygonal in cross section. The thread is carried longitudinally down one side of this member and up the opposite side thereof, and the said member is arranged to be turned 35 axially from time to time, whereby as one set of surfaces becomes fouled, a new set of surfaces may be brought into operation without stopping the machine. A number of these tubular members are arranged side by side in 40 a row, and the surfaces employed are to the left and right of an operator standing facing the members, so that both the downgoing portion of the thread and the upgoing portion thereof are visible to the operator and immediately accessible to him. I also provide 45 means whereby the returning end of the thread is caused to travel laterally across the surface of the contact member, so that a rolling or twisting action may be given to the thread in order that the same may be polished and lustered uniformly on all sides.

My invention also consists in many novel details of construction and combinations of parts as will hereinafter be more fully set 50 forth, and in order that my invention may be thoroughly understood, I will now proceed to

describe an embodiment thereof, having reference to the accompanying drawings illustrating the same, and will then point out the novel features in claims.

In the drawings: Figure 1 is a view in side elevation of a portion of a machine embodying my invention, a large portion thereof being broken away in order to save space, said broken away portion, however, containing 65 mechanism which is in the main a mere duplication of the mechanism illustrated. Fig. 2 is a view in vertical transverse section through the machine. Fig. 3 is a detail view in partial side elevation and partial vertical 70 section, on an enlarged scale, of one of the contact members and certain correlated parts. Fig. 4 is a similar view at right angles thereto. Fig. 5 is a detail sectional view thereof upon the line 5—5 of Fig. 3. Fig. 6 is a detail top 75 view showing particularly take-up mechanism for one of the threads. Fig. 7 is a detail top view showing particularly the let-off mechanism for one of the threads and the means for applying solution thereto. 80

The frame of the machine comprises a plurality of standards 10, a longitudinal top sill 11, a middle sill 12, upper horizontal side members 13, and lower horizontal side members 14 (see particularly Fig. 2). The top 85 sill 11 forms a support for laterally extending brackets 15 upon either side thereof, said brackets arranged to support and carry baths 16 for the solution. Each of said brackets 15 also supports and carries bearing members 17 90 for a reel or bobbin 18, a solution applying roll 19, a brush 20, an idler direction pulley 21, and guides 22, 22.

It may be here noted that, except for the driving mechanism, the machine as a whole 95 is exactly alike upon opposite sides of the central longitudinal plane thereof, and that each side of the machine comprises a plurality of similar mechanisms, each adapted to treat a thread or filament.

Each of the upper and lower horizontal side members 13 and 14 carries a set of brackets 23 and 24 respectively, each pair of brackets 23 and 24 constituting the support for a hexagonal tube 25 which constitutes the 105 contact member.

Referring more particularly to Figs. 3, 4 and 5, the brackets 23 and 24 will be seen to be provided with projecting threaded portions 26 to which is fitted a cylindrical tube 110 27. The hexagonal tube 25 is mounted loosely upon the said tube 27, as will be

readily seen by reference to the drawings. The lower bracket 24 is hollow and is provided with a steam inlet pipe 28 and a nozzle 29 uprising therefrom and penetrating to the 5 interior of the tube 27, and with a discharge or outlet pipe 30. The said pipes are arranged for the circulation of a heating medium such as steam, steam being conveniently admitted through the pipe 28 to the interior 10 of the tube 27, and the pipe 30 carrying off waters of condensation therefrom. A direction pulley 31 is provided beneath the bracket 24, said direction pulley being arranged to revolve freely upon cone points or other bearing 15 members carried by the said bracket, the diameter of the said direction pulley being just about equal to the distance between opposite faces of the contact member 25. The upper bracket 23 carries a direction pulley 32, 20 the working face of which lies in substantially the plane of one of the surfaces of the said contact member 25. The direction pulley 32 is preferably arranged to rotate about a center eccentric to its working face, the re- 25 sult being that, as the said pulley revolves, the edge thereof works backwards and forwards in the plane of the said surface, whereby a thread carried from the direction pulley 31 over the said direction pulley 32 and resting 30 upon a contact surface of the member 25 will be caused to move backwards and forwards over the said contact surface, as will be well understood.

The middle sill 12 forms a support for 35 brackets 34, which carry bearings 35 for take-up rolls or bobbins 36, and with brackets 37 which carry shafts 38 provided with driving wheels 39. The driving wheels 39 engage whirls 40 carried by the said bobbins 36, whereby they may be driven in the usual manner. The shafts 38 are connected together by suitable gearing 41, and are driven by means of a bevel gear connection 42 and the vertical shaft 43; and another 45 bevel gear connection 44 by a friction drive 45 through which variations of speed may be imparted, as may be desired. Traversing thread guides 46 are supported by the upper horizontal side members 13, said traversing 50 thread guides being driven by means of a cam 47 and gearing 48 connecting with one of the shafts 38, or by any other suitable means as may be convenient.

In operation the threads to be treated and 55 wound upon rolls or bobbins 18, are mounted in the machine by inserting the trunnions of the said rolls or bobbins 18 in the bearings 17. Each thread is then taken through a guide 22 over a solution applying roller 19, 60 through another guide 22, over a brush 20, around a direction roller or pulley 21, down over one of the surfaces of a contact member 25, around a bottom direction roller 31, up the opposite contact surface 65 of the member 25, around an upper direction

roller 32, over a guiding element carried by one of the traversing guide bars 46, and on to a take-up bobbin 36. The rotation of the shafts 38 will rotate the bobbins 36, and, in winding up the threads thereon, 70 will draw the threads from the reels or bobbins 18 over and across the mechanism just described. Each thread will receive its solution from a roller 19, the excess solution being wiped off by a brush 20, and will be 75 ironed, polished and lustered by means of the contact member 25. The travel of the thread will cause the upper direction roller 32 to rotate, and will thereby give the movement 80 above described to the thread across the surface of one of the contact surfaces of the member 25, this movement taking place, as it will be noticed, upon one side only of a member 25, and to the greatest extent near the discharge end thereof. This is advanta- 85 geous as the thread, in coming to the contact member quite wet, tends to foul the surface near the approach end, and to attempt to rub the thread across a fouled surface would be to foul the thread. Further, the thread, 90 in the first part of its movement over the contact member, merely gets dried, while the polishing and lustering takes place toward the latter part of such movement. It is while the polishing and lustering is 95 being effected that it is desirable to move the thread laterally across the face of the contact member.

Whenever a surface or a pair of surfaces of any of the contact members 25 has become fouled, it is only necessary to give the member a partial turn to bring up a fresh set of surfaces, whereby the machine may be kept running continuously. It is a simple matter to clean the fouled surfaces 100 after the members have been thus turned to bring fresh surfaces into operation. It will also be noted that, because the threads pass over the contact surfaces from left to right of the operator as he stands facing the 105 side of the machine, the said threads are accessible at all times, may be watched at all times, and, should a thread break, such thread may be readily tied and started again; and, furthermore, in first threading up the 110 machine, the operator can readily reach every part thereof and can retain control of the thread at all times.

What I claim is:

1. In mechanism of the class described, 120 the combination with means for applying a finishing solution to threads, and take up means for the threads, of heated contact members for the said threads, said heated contact members comprising a plurality of 125 vertically disposed tubes, one for each thread and means for guiding the threads longitudinally along the faces of the said tubes, the said tubes being rotatably mounted.

2. In mechanism of the class described, 130

the combination with means for applying a finishing solution to threads, and take up means for the threads, of heated contact members for the said threads, said heated contact members comprising a plurality of vertically disposed tubes, one for each thread and means for guiding the threads longitudinally along the faces of the said tubes, the said tubes being polygonal in cross section and rotatably mounted, whereby fresh surfaces may be presented for contact with the threads.

3. In mechanism of the class described, the combination with means for applying a finishing solution to threads, and take-up means for the threads, of heated contact members for the said threads, said heated contact members comprising a plurality of vertically disposed rotatably mounted tubes, one for each thread, and means for guiding the thread along the faces of the tubes, and for simultaneously vibrating the threads near the take-up ends thereof laterally across the faces of the said tubes.

25 4. In mechanism of the class described, the combination with means for applying a finishing solution to threads, and take-up means for the thread, of heated contact members for the said threads, said heated contact members comprising a plurality of vertically disposed tubes, one for each thread the said tubes being polygonal in cross section and rotatably mounted, whereby fresh surfaces may be presented for contact with the threads, and means for guiding the thread longitudinally along the faces of the said tubes, and for simultaneously vibrating the threads near the take-up ends thereof laterally across the faces of the said tubes.

40 5. In mechanism of the class described, the combination with means for applying a finishing solution to threads, and take-up means for the threads, of a heating system including a plurality of closed parallel pipes arranged to permit the circulation of a heating fluid therethrough, a plurality of tubes rotatably mounted upon the said pipes whereby they will receive the indirect heat of the heating fluid only, each said tube constituting a contact member for a thread to be treated, and means for guiding the threads longitudinally along the faces of the said contact members.

6. In mechanism of the class described, the combination with means for applying a finishing solution to threads, and take-up means for the threads, of a heating system including a plurality of closed parallel pipes arranged to permit the circulation of a heating fluid therethrough, a plurality of tubes rotatably mounted upon the said pipes whereby they will receive the indirect heat of the heating fluid only, each said tube constituting a contact member for a thread to be treated, and means for guiding the threads

longitudinally along the faces of the said contact members, the said tubes being polygonal in cross section and arranged to be held stationary during the normal operation of the device but to be rotated at will to present fresh 70 surfaces for contact with the threads.

7. In mechanism of the class described, the combination with means for applying a finishing solution to threads, and take-up means for the threads, of a heating system 75 including a plurality of closed pipes arranged normally in parallel relation, and means for circulating a heating fluid therethrough, tubes polygonally shaped in cross section rotatably mounted upon the said pipes, each 80 said tube constituting a contact member for a thread to be treated, and means for guiding the thread longitudinally along the two opposite faces of each of the said contact members and for vibrating the said thread 85 laterally across the faces of the contact member upon the return side thereof.

8. In mechanism of the class described, the combination with means for applying a finishing solution to threads, and take-up 90 means for the threads, of a heating system comprising a plurality of brackets 24 inclosing steam chambers, closed tubes 27 supported by the said brackets, nozzles 29 for admitting steam to the interior of the pipes 27 95 and discharge pipes 30 for carrying away exhaust steam and waters of condensation from the chambers within the brackets 24, tubes rotatably mounted upon the said vertical pipes, said tubes constituting contact members for individual threads to be treated, and means for guiding the thread longitudinally along the faces of the said tubes.

9. In apparatus of the class described, the 105 combination with means for applying a finishing solution to threads, and take up means for the threads, of heated contact members for said threads comprising three or more vertically arranged tubes, one for 110 each thread disposed in a row with their axes substantially in a plane, and guiding means for the threads for guiding the same longitudinally down one side of the said tubes and up the other side thereof, the portions of the threads upon both sides of the said tubes lying substantially in the plane of the axes of the tubes, whereby they may all be accessible from the front of the row of contact members.

10. In apparatus of the class described, the combination with means for applying a finishing solution to threads, and take up means for the threads, said take-up means comprising a longitudinal shaft having 125 means thereon for driving a plurality of individual bobbins, one for each thread to be treated, of heated contact members for the said threads comprising a plurality of vertically arranged tubes, one for each thread, 130

- disposed in a row with their axes substantially in a plane, the said plane being parallel with the axis of rotation of the said shaft, and guiding means for the threads for guiding the same longitudinally down one side of the said tubes and up the other side thereof, the said threads upon both sides of the said tubes lying substantially in the plane of the axes of the tubes.
- 10 11. In apparatus of the class described, the combination with means for applying a finishing solution to threads and take up means for the threads, of two rows of heated contact members for the threads, each row comprising a plurality of vertically arranged tubes, one for each thread, disposed side by side with their axes substantially in a plane, the said take up means comprising two rows of elements disposed back to back between the two rows of heated contact members and two parallel driving shafts, the axes of which are parallel with the planes of the axes of the tubes, and guiding means for the threads for guiding the same longitudinally down one side of the said tubes and up the other side thereof, the portions of the threads upon both sides of the tubes in either

row lying substantially in the plane of the axis of the tubes of that row, whereby the said portions will be readily accessible from 30 the front of the said row

12. In mechanism of the class described, the combination with means for applying a solution to threads, and a heated contact surface for the threads, of an eccentrically 35 mounted guiding roller the axis of which is arranged at right angles to the plane of the contact surface.

13. In mechanism of the class described, the combination with means for applying a 40 finishing solution to threads, of a heated contact member comprising a vertically arranged tube, means for guiding the thread down one side of the tube, a guiding roller beneath the tube for directing the thread 45 longitudinally along the opposite side of the tube, and an eccentrically mounted guiding roller at the upper end of the tube, the axis of said guiding roller being substantially at right angles to the axis of the said tube.
